UNITED STATES PATENT OFFICE.

JOHN B. HOEN, OF PHILADELPHIA, PENNSYLVANIA, ASSIGNOR TO THE FRANK A. ROLLING CO., INC., A CORPORATION OF PENNSYLVANIA.

SILVER-CLEANER.

1,182,173.

Specification of Letters Patent.

Patented May 9, 1916.

Application filed February 21, 1916. Serial No. 79,638.

To all whom it may concern:

Be it known that I, JOHN B. HOEN, a citizen of the United States, residing at Philadelphia, county of Philadelphia, and State 5 of Pennsylvania, have invented certain new and useful Improvements in Silver-Cleaners; and I do hereby declare the following to be a full, clear, and exact description of the invention, such as will enable others 10 skilled in the art to which it appertains to make and use the same.

It is the object of the present invention to provide means whereby tarnished metal articles, such as silverware, either solid or 15 plated, mesh bags, toilet articles and the like, and articles of gold and other electro-negative metals, may be quickly and effectively cleaned of the tarnish by electrolytic action instead of or preparatory to polishing.

The silver or other articles to be cleaned are immersed in an alkaline solution in conjunction with an apparatus so constructed that the silver or the like becomes the 25 cathode of a voltaic couple, and the coating or tarnish is electrolytically reduced by the electric current thus set up, and the silverware thereby rendered clean and bright.

According to the present invention, the 30 apparatus whereby this result is effected is economical to manufacture, compact in design, rugged in construction, efficient in its electro-chemical action, and convenient to use and clean.

In the drawings Figure 1 is a plan view 35 of an apparatus suitable for carrying out the results desired; Fig. 2 is a sectional elevation thereof on the line 2-2 of Fig. 1; and Fig. 3 is an enlarged fragmentary elevation.

In the construction shown there is provided an electrode 1 of circular outline having a flat top, and having at its edge a downwardly extending flange in the form 45 of a circumferential bead 2 (Fig. 2) which stiffens said flat top and raises it above the bottom of the dish pan or other container in which the apparatus is to be used, as indicated in dotted lines in Fig. 2. This electrode or disk 1 consists of electro-positive metal, as, for example, zinc, and its flat top has one or more perforations 3 communicating with the shallow pocket formed between this flat top and the bottom of the 55 dish pan or container. Secured to the zinc

electrode and in effective electrical connection therewith is a grid adapted to receive and support the articles to be cleaned and to maintain good electrical connection between said articles and the zinc. The grid 60 preferably covers substantially the entire top face of said electrode and has a contacting surface which is of a metal or alloy electro-positive to the zinc, as, for example, tin, silver, solder, gold, etc. Preferably the 65 exposed surface is of tin.

In the embodiment illustrated, the tinned grid includes a pair of segmental brackets 4 and 5 preferably of round wire, opposed to one another, and spaced from the flat 70 top of the disk near its periphery but with flattened ends 6 and 7 offset at 8 and 9 (Fig. 2) and soldered to the flat top of the disk so that there may always be good electrical connection between the disk and the 75 brackets. Supported on these brackets and preferably made integral therewith by welding, are a plurality of cross-bars 10, preferably in the form of separate, straight, round rods of progressively varying length. 80 If iron is used for the brackets and cross-bars, the entire grid should be heavily tinned after welding, so that when assembled with the disk, it will throughout present an exposed surface electro-negative 85 to the zinc and well adapted for making contact with the silverware to be cleaned.

The electrolyte used in the dish pan or other container of Fig. 2, when silverware or the like is to be cleaned, is an alkaline 90 solution prepared, for instance, by dissolving one tablespoonful of baking soda (bicarbonate of soda) and one-half cup of table salt (sodium chlorid) in each gallon of water. Preferably, but not necessarily, 95 warm or hot water is used. When this electrolyte is poured into the dish pan or other container wherein the cleaning is to be carried out, there will be set up an electrolytic action by which the zinc or disk 1 will tend 100 to pass into solution and reducing agents will be liberated on the tinned wire grid, thereby reducing any oxid on the grid and rendering it bright and therefore in good condition for making effective electrical contact with any silverware or other articles put into the dish pan for cleaning. Owing to the quick polarization of the tinned wires and to the high "over-voltage" of the tin, the total flow of current from the zinc to the 110

wires when no silverware is in the dish is relatively small. Silverware or other articles to be cleaned are then immersed in the electrolyte and by resting on the cleaned tinned wires are placed in electrical connection with the zinc of the disk so that current can flow from the zinc or electro-positive metal through the electrolyte to the silverware with simultaneous electrolytic reduction 5 of the oxids, sulfids and the like, which constitute the layer of tarnish on the silverware. The articles clean very quickly and come out bright and of good appearance, and there is no removal of silver from the 10 surface of the articles but merely an electrolytic reduction of the tarnish. The articles may then be rinsed in clear water and rubbed with a soft cloth.

During the electrolytic action the tinned 20 grid remains clean and bright, but the zinc or electro-positive metal of the disk becomes coated with a porous film or incrustation. However, the soldered connection between the wire grid and the zinc dish maintains 25 effective electrical connection between the silverware and the zinc, and the film or incrustation on the zinc or other electro-positive metal is porous enough to allow the electrolytic action to go on, so that in practice, the operation may be continued for 30 long periods without substantial loss in efficiency. Aluminum can be used for the electro-positive disk 1 and nickel-plated wires can be used for the metal grid.

By making the cross-bars 10 of the grid integral with the peripheral segments 4 and 5 as by welding thereto, a high electrical conductivity is insured, and there is no chance of loose contacts in the path of electric current flowing from the silverware to the zinc, and by making the grid large enough to substantially cover the flat top of the disk, and with the cross-bars 10 relatively close together, as illustrated, the silverware cannot work down under the grid where it might remain uncleansed because of the insulating film or incrustation which forms on the zinc.

By making the grid of the construction shown, the segmental brackets 4 and 5 are so opposed to one another and are so braced by the cross-bars 10 that the grid is substantially rigid and not likely to collapse under the weight of the silverware being cleaned, 55 nor when the disks are stacked one above another for shipment in bulk. Also, by spacing the tinned wires 10 well above the flat surface of disk 1, there is a good distribution of current through the electrolyte, 60 and an equalization of the electrolytic action on the zinc, such as would not be had if the cross-bars 10 rested directly on the zinc surface. This arrangement also tends to equalize the electrolytic action throughout 65 the entire surface of the silver articles.

being cleaned, instead of confining it to limited areas as might be the case if the electrolytic path between the zinc and the articles to be cleaned was very short at any point.

By making the zinc electrode of circular outline it fits well in the bottom of a dish pan, or the like, and the circumferential bead holds the flat face of the disk spaced above the bottom of the dish pan so that the electrolyte may contact not only with the top face, but also with the bottom face of the disk. The opening 3 through the disk permits the escape of air which might otherwise become entrapped under the disk, and it also affords a path for current through the electrolyte to the under-surface of the disk, and while the flow of current through this opening will ordinarily not be large, any impairment in the effectiveness of the top face of the disk, as through abuse of the apparatus, will not render the device inoperative, for current can still flow to the lower face of the disk and cleaning will still go on, though at a slower rate.

It has been found in practice that housewives in order to keep the electrolyte warm, and therefore in most effective condition, often place the dish pan on a stove, and with the present arrangement the perforation through the disk permits limited circulation of electrolyte from beneath the disk or the escape of steam from beneath in case of too energetic heating, and the zinc plate is protected from such detrimental action as might result to the zinc or to its incrustation, were there no layer of electrolyte between the zinc and the bottom of the pan. The low thermal conductivity of zinc and of the incrustation which forms on its active surface as an incident to use as described herein, limits the transfer of heat through the disk and gives a particular importance to the pocket bounded by the circumferential flange of the disk and filled always with electrolyte which is in connection with the main body of the electrolyte through opening 3. By making the active surface of the zinc flat, and by spacing the grid well above that flat surface, the cleaning and drying of the active surface may be readily effected.

Changes in the apparatus shown in the drawing may be made without departing from the invention as defined by the appended claims.

I claim:

1. Apparatus for the electrolytic cleaning of silverware and the like, comprising a zinc electrode of circular outline having at its edge a stiffening flange, and a grid consisting of segmental wire brackets opposed to one another and spaced from the top of said electrode near its periphery, and cross-bars secured to said brackets and having a surface of tin.

2. Apparatus for the electrolytic cleaning of silverware and the like, comprising a zinc electrode of circular outline to fit the bottom of a dish pan, and a grid for said electrode consisting of segmental wire brackets opposed to one another and spaced from the top of said electrode near its periphery but with off-set ends soldered to said top, and cross-bars lying across said brackets and secured thereto, said cross-bars and brackets having a surface of tin. 5
3. Apparatus for the electrolytic cleaning of silverware and the like, comprising a zinc electrode having a flat top and having at its edge a downwardly extending flange, said flat top having an opening permitting the escape of air or steam from beneath said electrode and affording a path for current from the bottom face thereof, and a grid 10 for said electrode consisting of wire brackets opposed to one another and spaced from said flat top near its periphery, but with off-set ends soldered to said top, and cross-bars lying across said brackets, said cross-bars 15 and brackets having a surface of tin. 20
4. Apparatus for the electrolytic cleaning of silverware and the like, comprising a zinc electrode of circular outline having a flat top and having at its edge a downwardly extending circumferential flange, said flat top having an opening permitting the escape of air or steam from beneath said electrode and affording a path for current from the bottom face thereof, and a grid 25 for said electrode comprising opposed brackets and straight tinned bars secured thereto and spaced from the flat top of said electrode to facilitate cleaning thereof and adapted to receive and support the articles to be 30 cleaned, said grid maintaining good electrical connection between said articles and the zinc. 35
5. Apparatus for the electrolytic cleaning of silverware and the like, comprising a zinc electrode of circular outline having a flat top and having at its edge a downwardly extending circumferential flange, said flat top having an opening permitting the escape of air or steam from beneath said electrode and affording a path for current from the bottom face thereof, and a grid 40 for said electrode consisting of opposed wire brackets and tinned wires welded thereto and spaced from the top of the electrode to 45 equalize the flow of current therefrom, and to facilitate cleaning of the electrode, said wires being adapted to receive and support the articles to be cleaned and to maintain good electrical connection between said articles and the zinc. 50
6. Apparatus for the electrolytic cleaning of silverware and the like, comprising a zinc electrode of circular outline having a flat top and having at its edge a downwardly extending circumferential flange, said flat top having an opening permitting the escape of air or steam from beneath said electrode and affording a path for current from the bottom face thereof, and a grid for said electrode consisting of segmental wire 55 brackets opposed to one another and spaced from said flat top near its periphery, but with off-set ends soldered to said top and cross-bars lying across said brackets and welded thereto, said cross-bars and brackets 60 having a surface of tin. 75
7. Apparatus for the electrolytic cleaning of silverware and the like, comprising a zinc electrode of circular outline having a flat top and having at its edge a downwardly extending circumferential bead to stiffen said flat top and to raise it above the bottom of the container in which the electrolyte is held, said flat top having an opening permitting the escape of air or steam from beneath said electrode and affording a path for current from the bottom face thereof, and a grid for said electrode consisting of segmental wire brackets opposed to one another and spaced from said flat top near its 70 periphery, but with off-set ends soldered to said top and cross-bars secured to said brackets, said cross-bars and brackets having a surface of tin. 80
8. Apparatus for the electrolytic cleaning of silverware and the like, comprising a zinc electrode of circular outline having a flat top and having at its edge a downwardly extending circumferential bead to stiffen said flat top and to raise it above the bottom 85 of the container in which the electrolyte is held, said flat top having an opening permitting the escape of air or steam from beneath said electrode and affording a path for current from the bottom face thereof, and a grid for said electrode consisting of segmental wire brackets opposed to one another and spaced from said flat top near its 90 periphery, but with off-set ends soldered to said top and cross-bars secured to said brackets, said cross-bars and brackets having a surface of tin. 95
